UNITED STATES PATENT OFFICE.

CHARLES A. CASE, OF NEW YORK, N. Y., ASSIGNOR TO CASE TUNNEL & ENGINEERING COMPANY, OF NEW YORK, N. Y., A CORPORATION OF ARIZONA TERRITORY.

TRAMWAY-BUCKET GRIP.

No. 904,178.

Specification of Letters Patent.

Patented Nov. 17, 1908.

Application filed April 4, 1907. Serial No. 366,304.

To all whom it may concern:

Be it known that I, CHARLES A. CASE, a citizen of the United States, and a resident of the borough of Manhattan, in the county of New York and State of New York, have invented certain new and useful Improvements in Tramway-Bucket Grips, of which the following is a specification.

This invention relates to tramway bucket grips. Its organization comprises a gripping mechanism which when connected to an element, such as a frame, platform, bucket and the like, allows said element to be easily propelled in curved paths as well as along straight runs of track or tramway. Its construction is specifically applicable to aerial tramways, and comprises essentially a couple of grips which are pivoted to said element, and clamped to a running rope that runs in curved as well as straight directions. The grips will follow said straight and curved directions and the said elements will remain suspended in equilibrium from their overhead supports.

More specifically the invention comprises essentially a pair of grips pivoted to the frame of a trolley bucket of an aerial tramway. The grips are clamped to a running rope, and being capable of swinging to the right or left allow the said frame to permit the running rope to turn to the right or left around curves, while the bucket is maintained in equilibrium.

In the accompanying drawings, Figure 1 shows the invention with an elevation of a curved aerial tramway station, Fig. 2 represents partial sections of Fig. 1 on the lines 2, 2 and 2^a, 2^a, Fig. 3 represents a section of Fig. 2 about on the line 3, 3, Fig. 4 shows an enlarged side view of an aerial tramway trolley bucket with the invention connected thereto, Fig. 5 shows an end view of Fig. 4, Fig. 6 is an enlarged portion of Fig. 4, Fig. 7 represents an end view of Fig. 6, Fig. 8 shows a section of Fig. 6 on the line 8, 8, Fig. 9 is a partial section of Fig. 6 on the line 9, 9.

Referring particularly to Figs. 1 to 3 there is represented the frame work of a curved station for an aerial tramway, in which are supported curved tracks 20 with the shoes 21. The tracks 20 connect with the track ropes 22, which latter lead over guide sheaves 23 in the station. In the framing of the station are pivoted guide

rollers 24 and 25 for the running rope 26 and its return 27, guard rails 62 being located over the rollers 24 and 25. On the tracks 20 are supported the trolley wheels 35 of the bucket frames 36 of the buckets 32. From the lower ends of the latter extend the grips 37 that clamp the running rope 26. The latter rope engages with the guide rollers 24 and 25.

Referring now particularly to Figs. 4 to 9, the trolley wheels 35 are journaled in the side plates 38, from which is suspended on a pivot 39 the frame 36. A bucket 32 is pivoted in the frame 36. Locking devices 41 are connected up between the said bucket and frame 36. To the lower ends of the frame 36 are fastened the lugs 45, which support the eye bolts 46. On pins 47 carried in the eye bolts 46 are pivoted the adjusting straps 48 in which latter are supported pins 49, at right angles to the pins 47. The straps 48 carry the gripping yokes 50 that have the concaved toes 51 and the flanges 52. The flanges 52 support the tee bolts 53, each of which have slots 54 for supporting the adjusting grip straps 55. The latter straps have openings 56 for the ends 57 of the tee bolts 53.

To use the invention the trolley wheels 35 are located when in a station on the tracks 20, the running rope 26 or its return 27 pulling the trolley with its load. When the trolley runs around curved tracks the adjustable grips swing to either side and under the frame 36 which allows the said running rope to engage with the rollers 24 and 25 and still allow the buckets to swing plumb from the trolleys. The pins 47 allow the grips to swing to the right or left of the frames 36, and the pins 49 allow the grips to adjust themselves in planes at right angles to the adjustments secured by the pins 47. The hole 60 in the yoke 50 being somewhat larger in diameter than the pin 49 connected with adjusting strap 48, constitutes secondary adjusting means between the rope 26, 27 and the frame 36 of the bucket. The guard rails 62 prevent the frame 36 striking the rollers 24, 25, as the bucket is passing around a curve.

Having described my invention I claim:

1. In a tramway bucket grip the combination of an eye bolt, an adjusting strap pivoted thereto, a gripping yoke pivoted to the adjusting strap, a bolt extending from the

gripping yoke, an adjusting grip strap extending from the bolt and clamping a running rope to the gripping yoke.

2. In a tramway bucket grip the combination of a bolt, a pin supported in the bolt, an adjusting strap pivoted on said pin, a pin supported in the adjusting strap at right angles to the pin supported in the bolt, a gripping yoke having concaved toes pivoted 10 on the latter pin, flanges extending from the gripping yoke, bolts adjustably secured to said flanges, an adjusting strap supported by each of the bolts and clamping a running rope in the concaved toes of the gripping 15 yoke.

3. In a tramway bucket grip the combination of an eye bolt, a pin supported in the eye bolt, an adjusting strap pivoted on said pin, a pin supported in the adjusting strap 20 at right angles to the pin in the eye bolt, a gripping yoke having flanges and supported on the pin in the adjusting strap by means of an opening larger in diameter than the latter pin to allow adjustment, tee bolts adjustably supported in the flanges of the 25 gripping yoke, an adjusting strap supported on each of the tee bolts and clamping a running rope to the gripping yoke.

4. The combination of a trolley, a grip 30 pivoted at the forward end of the trolley and a grip pivoted at the rear end of the trolley, and a running rope clamped by the grips.

5. The combination of a trolley, a frame 35 extending from the trolley, a grip pivoted at the forward end of the said frame and a grip pivoted at the rear end of the frame, and a running rope clamped by the grips, so that the grips can swing under the said frame 40 when the running rope is passing around a curve.

6. The combination of a track, a trolley supported thereon, a frame extending from the trolley, a pair of grips pivoted from the 45 frame so as to swing under and to either side thereof, and a running rope taking straight and curved paths connected to the grips.

7. The combination of an aerial track rope, a trolley supported thereon, a frame extending 50 from the trolley, an adjusting strap pivoted at the forward end and also at the rear end of the frame, a gripping yoke pivoted in each of said straps, a pair of tee bolts extending from each gripping yoke, an adjusting grip strap supported on each tee bolt,

and a running rope clamped between the said grip straps and the gripping yokes.

8. The combination of a track, a trolley supported thereon, a frame pivoted on the trolley, an adjusting strap pivoted at the forward end of the frame, and an adjusting strap pivoted at the rear end of the frame, so that the straps can swing to either side of the frame of the trolley, a gripping yoke pivoted in each of said adjusting straps so as to 60 swing at right angles to the direction of swinging movement of the said strap, a pair of adjusting grip straps connected with each gripping yoke to clamp a running rope. 65

9. The combination in an aerial tramway 70 of a track rope, a trolley supported on said rope, a frame pivoted from the trolley, a bucket supported in the frame, a grip pivoted to the forward end of the frame, and a grip pivoted to the rear end of the frame, a running 75 rope clamped to the grips, which latter are capable of swinging under the frame to the right and left thereof when the running rope is passing around a curve.

10. The combination in an aerial tramway 80 of a track rope, a trolley supported on said rope, a frame pivoted from the trolley, a bucket supported in the frame, a grip pivoted to the forward end of the frame, and a grip pivoted to the rear end of the frame so as 85 to swing to either side of the frame, a second pivot connected up with each grip to allow it to swing at right angles to the motion obtained by swinging to the right and left, and a running rope connected with the grips. 90

11. The combination in an aerial tramway 95 of a track rope, a trolley supported on said rope, a frame pivoted from the trolley, a bucket supported in the frame, a grip pivoted to the forward end of the frame, and a grip pivoted to the rear end of the frame so as to swing to either side of the frame, a second pivot connected up with each grip to allow it to swing at right angles to the motion obtained by swinging to the right and left, a running rope connected with the grips, and secondary adjusting means between the 100 running rope and the said frame. 100

Signed at the borough of Manhattan in the county of New York and State of New 105 York this 30th day of March A. D. 1907.
